Clarence D. Kerr

Patented June 23, 1925.

UNITED STATES PATENT OFFICE.

ROBERT R. RUST, OF NEW YORK, N. Y.

WATER HEATER.

Application filed August 22, 1922. Serial No. 583,534.

To all whom it may concern:

Be it known that I, ROBERT R. RUST, a citizen of the United States, residing in the city of New York, county of Queens, and State of New York, have invented new and useful Improvements in Water Heaters, of which the following is a specification, reference being had to the accompanying drawings, in which:—

10 Fig. 1 is a section of my improved heater and Fig. 2 is a section on lines II—II of Fig. 1.

My invention relates to water heaters and comprises a double walled vessel in which 15 the heating medium passes through a chamber between the walls of the vessel and the water to be heated passes through the chamber contained within the interior wall. The interior wall of the cylinder is convoluted 20 in form, so as to afford an extended heating area. My improved apparatus is arranged so that it may be assembled readily and is particularly adapted for use in heating water in a domestic hot water system. My 25 invention also comprises the various features which I shall hereinafter describe and claim.

Referring to the drawings, 2 indicates the water heating chamber which is formed 30 with convoluted shell 3 and is contained in a cylinder 4 which forms with the outer face of the shell 3 a chamber 5 for the heating medium. The chamber 2 has tapped openings 6 and 7, the opening 6 being the inlet and the opening 7 being the outlet. 35 The upper end of the shell 3 has an annular flange 8 which is machined and engages a machined face 9 in the opening which occupies substantially the whole top of the cylinder 4. The machined faces on the member 2 and cylinder 4 are arranged at differential angles, the angle of the face 8 being preferably two degrees and that of the face 9, $2\frac{1}{2}$ degrees, so that the face 8 40 will have a line contact with the face 9 on the cylinder. The bottom of the cylinder 4 is apertured at 10 for admission of the inlet pipe 11 and has a shoulder 12 for a gasket about the aperture 10 to provide a bearing 45 surface for a nut 13 which engages a thread 14 on the inlet pipe 11 and by which the shell 3 is drawn down so as to draw the face 8 into a tight engagement with the differentially tapered face 9 of the cylinder 4. The cylinder 4 is provided with tapped 50 openings 15 and 16 for the inlet and outlet

5 pipes 17 and 18 by which the heating medium is circulated into and through the cylinder and around the convolutions of the chamber 2 and is returned to the source of 60 heat. The cylinder 4 is also provided with an additional tapped opening 19 which may be used for a connection with the source of heat instead of opening 17 which may then be closed by a plug.

When in use my heater may be heated by 65 hot water circulation or by steam or vapor. The heating medium enters the cylinder 4 through the inlet pipe 17 and then passes 70 between the cylinder wall 4 and the convoluted wall 3 of the chamber 2 and out the return pipe 18 to the boiler. The water to be heated enters the chamber 2 through the inlet opening 6 and is quickly heated by 75 convection from the heat of the water without the wall of the chamber 2 and, rising, passes out through the outlet opening 7. If desired, the inlet and outlet may be connected with a range boiler and will serve as 80 an auxiliary therefor, or they may be connected with a storage tank connected with a domestic supply system.

My invention is of great utility and provides an efficient and practicable heater in 85 which the convoluted shell enables the heating medium to act quickly upon the water to be heated. It is readily assembled or taken down, constructed as it is of two separate shells and a minimum number of parts. The use of the differential tapered joint at 90 the top connection between the two shells and a single nut for holding the parts in place provides an exceedingly simple and economical construction.

The terms and expressions which I have 95 employed are used as terms of description and not of limitation, and I have no intention, in the use of such terms and expressions, of excluding any mechanical equivalents of the features shown and described, or 100 portions thereof, but recognize that various structural modifications are possible within the scope of the invention claimed.

What I claim is:

1. A water heater comprising an inner shell for the water to be heated, an outer shell arranged about the inner shell and providing a chamber for the heating medium therebetween, the outer shell and inner shell being connected at one end by a differentially tapered joint and at the other end by means 105 for drawing the said differential joint into 110

tight engagement, the two shells being free from other connecting parts, said shells each having an inlet and an outlet.

2. A water heater comprising an outer shell and an inner shell, the outer shell having an aperture in one end of greater diameter than the body of the inner shell, the inner shell and the outer shell having differentially tapered surfaces arranged to be brought into engagement with each other, and a nut and thread connection for drawing the said parts into a line engagement.

3. A water heater comprising an outer shell and an inner shell, the outer shell having an aperture in one end of greater diameter than the body of the inner shell, the inner shell and the outer shell having at corresponding ends differentially tapered engaging surfaces, the inner shell at the oppo-

site end having an extension, a nut engaging said extension and having a bearing against the outer shell whereby, as the nut draws down on the said extension, the said differential surfaces at the other end of the device are drawn down into a line engagement.

4. A water heater comprising an outer shell and an inner shell, the outer shell having an aperture in one end of greater diameter than the body of the inner shell, and the inner shell having convolutions to provide an extended heating surface, meeting surfaces on said shells, one of said surfaces being inclined at a greater angle to the horizontal than the other to compensate for inequalities in said shells, and means for drawing said surfaces tightly into engagement.

ROBERT R. RUST.
